UNITED STATES PATENT OFFICE.

JULES CAZEAUX LAFOREST, OF THIBODAUX, LOUISIANA.

CHAIN PUMP AND THE LIKE.

Application filed December 6, 1921. Serial No. 520,233.

To all whom it may concern:

Be it known that I, JULES CAZEAUX LAFOREST, a citizen of the United States of America, and resident of Thibodaux, parish of La Fourche, Louisiana, have invented certain new and useful Improvements in and Relating to Chain Pumps and the like, of which the following is a specification.

This invention relates to certain improvements in endless water elevators; and the objects and nature of the invention will be understood by those skilled in the art in the light of the following explanations of the accompanying drawings illustrating what I now believe to be the preferred mechanical expression or embodiment of my invention from among forms, constructions and arrangements within the spirit and scope thereof.

Endless water elevators, such as so-called chain pumps, are often employed to a greater or less extent for drainage and other purposes in lifting water from a lower to a higher elevation where it is necessary for the pump to extend to a considerable depth into the body of water to be lifted or removed, often approximately to the bottom thereof so that the pump can operate until the water is practically exhausted, for instance, until a field or a well is approximately dry.

These pumps usually comprise an endless traveling chain of buckets hanging in parallel vertical plies from an upper driving sprocket and engaging a bottom idler sprocket near the bottom of the body of water so that one vertical ply of the chain is constantly descending through a more or less great depth of water while the other vertical ply is ascending and lifting water through a vertical trough or pipe to the discharge for the water elevated. This pipe extends from said discharge above the maximum water level down through the water and is open at its lower end usually near the bottom, to form the pump inlet through which the buckets pass inwardly in succession. More or less power is consumed in driving the buckets through the water on their return passage from the driving sprocket to the pump pipe inlet where the buckets start to ascend.

It is an object of my invention to so arrange and construct the pump features as to reduce to the minimum the power required to drive the buckets on their down or return

movement through the water; and a further object of the invention is to so arrange the pump pipe as to provide its water inlet along the path of movement of the buckets while 60 on their down or return passage.

With these and other objects in view, my invention consists in certain novel features in construction and in combinations and arrangements as more fully and particularly 65 explained and specified hereinafter.

Referring to the accompanying drawings:

Fig. 1 is a vertical section of a pump embodying my invention, the illustration being more or less diagrammatical. 70

Fig. 2 is a horizontal section on the line 2-2, Fig. 1, the structure being partially broken away and illustrated on an enlarged scale.

Fig. 3 is a detail perspective view on a reduced scale. 75

In the diagram illustrated, an endless flexible conveyer or elevator, is provided made up of uniformly-spaced buckets 1, of any suitable form and construction joined 80 together by any suitable means to form an endless series, as by flexible connections 2. These connections can be composed of one or more parallel endless lengths of sprocket chain or other suitable connections to carry 85 and support the buckets which are included in or otherwise secured to the endless connection, in any suitable manner.

For convenience in description, this endless elevator or connection that includes the buckets, is herein referred to as a "chain", using this term "chain" in a broad generic sense to cover and include any suitable flexible connection as well as what is strictly a chain. 95

The endless conveyer, the chain, is supported by and driven from a rotary driving member, such as sprocket 3, arranged a distance above the water level and carried by any suitable supports, not shown. This member 3 is provided with any suitable power or manually actuated driving means, although the power is usually derived from a suitable motor, not shown, applied to the member through driving pulley 3^a or the 100 equivalent thereof. The lower bight of the chain passes under and in mesh with an idler rotary drum or sprocket 4, carried by any suitable supports, not shown, and arranged, usually near the bottom of the body 105 of water in which the pump operates. 110

The chain hangs vertically from the up-

per to the lower sprocket to form a vertical descending ply and a vertical ascending ply.

A stationary pump pipe or casing (usually termed a trough) is supported by any suitable means (not shown) in the body of water with its inlet near the bottom thereof, and one end 6 of this casing extends vertically to a suitable elevation above the high water level and there has lateral opening 10 to water discharge 7. The endless chain travels longitudinally within this casing which in cross sectional formation approximates the form and outline dimensions of each bucket (the buckets being all approximately similar) so that each bucket will propel a body of water forwardly in the casing and lift the same to the discharge, broadly according to well known chain pump practice. According to generally followed chain pump practice the casing receives only a portion of the length of the vertical ascending ply of the chain, and is vertical throughout its length and open at its lower end where the ascending buckets enter.

Such chain pump construction as commonly employed, requires the submerged buckets, not in the comparatively short vertical casing, to waste force and consume power in traveling down, laterally and upwardly through the water until entering the lower end of the casing to perform water lifting work.

According to my present invention, I extend the approximately-closed water confining casing 6 of the pump down to and laterally under the idler drum and upwardly at the opposite side thereof to conform to the path traveled by the chain buckets in moving down to and under said 40 idler and upwardly to the water discharge, and so construct said pump casing that it receives the water to be elevated at its portion through which the buckets descend.

The lower part 8 of the casing in thus 45 U-shaped and approximately concentric with the axis of the idler drum, which drum fits down in the U between the vertical lengths of the casing and approximately closes the otherwise open top of the U where 50 the top wall thereof is removed to permit the chain to mesh with the drum or sprocket. The drum embodies a cylindrical wall or hub 4^a to form the top wall of the U portion of the casing and having approximately a 55 running fit with the edges of said casing.

The vertical length 9 of the pump casing that receives the descending buckets and that provides the pump inlet is of any suitable length in upward continuation of the 60 curved U portion 8 of the casing, although I prefer to extend the vertical inlet portion 9 to a point above the maximum water level. This inlet portion 9 of the casing is formed with submerged downwardly inclined water 65 inlets through which the water flows down-

wardly into the casing to enter the casing approximately in the direction of movement of the buckets descending in said inlet portion of the casing to thereby aid in reducing the power required to drive the buckets and consequently the load on the chain as an entirety.

In the particular example illustrated, I show the submerged part of the inlet portion of the casing provided approximately throughout its length with longitudinal series of spaced downwardly and inwardly inclined inlet slots, passages or openings 11 extending through its opposite side walls. These inlet passages are so formed and arranged that the buckets will sweep downwardly in the casing past the lower ends of the passages through which the passages discharge into the casing, and the water will be drawn into the casing through said passages in the form of downwardly flowing columns or bodies that will exert more or less downward force or pressure on the descending buckets.

The buckets successively pass from the inlet portion of the casing into the closed U bend and therefrom to and vertically in the vertical water discharge leg of the casing, and force successive bodies of water from said inlet portion and thereby cause constant downward flow into said portion through said inclined inlet passages.

It is evident that various changes, modifications and variations might be resorted to without departing from the spirit and scope 100 of my invention, and hence I do not wish to limit myself to the exact disclosures hereof.

What I claim is;

1. A so-called chain pump having a driven endless connection and series of 105 buckets, and a pump casing in which said buckets travel longitudinally to lift water to the pump discharge from said casing, said casing being continuous from a point above the water level where the buckets descend to the pump discharge where the buckets ascend, the submerged portion of the casing that receives the descending buckets being provided with water inlets.

2. A water elevator comprising an endless 115 traveling flexible connection provided with an endless series of buckets and a relatively fixed pump casing extending into the water to be elevated and enclosing the submerged portion of said connection and its buckets, 120 said casing embodying a vertical water inlet portion in which the buckets descend and a vertical water discharge portion in which the buckets ascend, the casing being continuous between said vertical portions at the 125 lower end of the elevator.

3. A water elevator comprising an endless series of water lifting buckets, means to drive said buckets successively in a circuit to descend along a vertical path in the water 130

to be elevated and laterally therefrom to ascend in a vertical path to the elevated water discharge, and a pump casing for said buckets and conforming to said paths, said 5 casing providing means to cause the water to enter the casing in the direction of movement of the buckets.

4. A water elevator substantially as described by claim 3, wherein the water inlet 10 portion of the casing is provided with a

longitudinal series of downwardly and inwardly inclined water inlet passages.

5. A water elevator such as required by claim 3, wherein the water inlet portion of the casing provides numerous water inlet 15 passages arranged longitudinally of said portion and formed and constructed to discharge numerous streams of water downwardly in said portion of the casing.

JULES CAZEAUX LAFOREST.
